UNITED STATES PATENT OFFICE

WALTER K. VOSS, OF DAVENPORT, IOWA

AGITATOR

Application filed February 27, 1930. Serial No. 431,701.

The present invention relates to agitators and more in particular to a novel construction of adjustable agitator for washing machines or the like.

Among the objects of the present invention are to provide a novel construction of agitator adapted to be mounted near the water line in a washing machine tub for affording the maximum cleansing action to the clothes that are being swished through the water.

Another object of the invention is to provide an agitator adapted to be readily adjusted to any height upon the agitator shaft for swishing the clothes through the water and for securing maximum washing efficiency.

The invention further comprehends the provision of an agitator provided with a designated marking or means for denoting to the operator the height or adjustment necessary for the most efficient washing point. This marking designates the water line and is in full view of the operator when the lid of the tub is in raised position, it being readily understood that the position of the agitator would vary in accordance with the depth of water in the tub.

A further object is to provide a novel construction of an agitator having a hub portion adapted to encompass the drive shaft and provided with radiating arms and depending impeller elements for swishing the clothes through the washing fluid, these elements being connected by means of an annular ring which adds strength and rigidity thereto.

A still further object of the invention is to provide an agitator upon a driving shaft which passes through the bottom of the tub so that the operator may have full view of the necessary setting or adjustment of the agitator.

A still further object of the invention is to provide a novel construction of sleeve adapted to slidably fit over the driving shaft passing through the tub and upon which the agitator is slidably and adjustably mounted. The agitator is preferably constructed of metal or other suitable material of greater specific gravity than the liquid in the tub in which it operates.

Further objects are to provide a construc-

tion of maximum simplicity, efficiency, economy, and ease of assembly, adjustment and detachment, and such further objects, advantages, and capabilities as will later more fully appear and are inherently possessed thereby.

The invention further resides in the combination, construction and arrangement of parts illustrated in the accompanying drawings, and while I have shown therein a preferred embodiment, it is to be understood that the same is susceptible of modification and change, and comprehends other details, arrangements of parts, features and constructions, without departing from the spirit of my invention.

Referring to the drawings:

Fig. 1 is a view in vertical cross section through a washing machine tub and the novel construction of agitator and sleeve therefor.

Fig. 2 is a view in perspective of the sleeve and agitator adjustably mounted thereon.

Referring more particularly to the drawings, the embodiment selected to illustrate the invention is shown as comprising a washing machine tub or the like 1 provided with a bottom 2, top 3, which is adapted to be provided with hinges or the like for permitting ready opening and closing of the tub, 80 and an agitator or driving shaft 4 passing centrally through the bottom of the tub and extending to a position adjacent the top of the tub. This shaft is given an oscillatory movement by mechanism not disclosed, and in turn oscillates an agitator 5.

Mounted upon the bottom of the tub, is a sleeve or hollow pedestal 6 through which the shaft 4 passes. Seated upon this sleeve or hollow pedestal is a tubular member or sleeve 7 having reduced portions 8 and 9 at the ends thereof and an enlarged portion 10 intermediate such reduced ends, this sleeve being secured to the shaft 4 by any suitable means such as a pin or the like. 95 Longitudinally extending grooves 11, on opposite sides of the sleeve or tubular member 7, extend from adjacent the reduced portion 9 to substantially the bottom of the body portion, but leaving a shoulder 12 adjoin-

ing the reduced portion 8. The longitudinally extending grooves or channels 11 are provided with an enlarged portion 13 at the bottom thereof. These grooves or channels are adapted to receive longitudinally extending ribs or projections 14 on the hub 15 of the agitator 5 whereby the agitator is made slidable on said sleeve 7.

10 A thumb nut 16 threadedly engages the hub 15 and passes through one of the ribs or extensions 14, whereby the end of this thumb nut may impinge against the inner wall of one of the channels 11 and thus hold the agitator 5 in any desired position of 15 adjustment.

10 The hub 15 of the agitator 5 is provided with an enlarged downwardly projecting skirt 17 provided with a plurality of arms or spokes 18 merging into downwardly depending blades or the like 19. The upper portion of the depending blade is connected to or formed integral with an annular ring 20 for strengthening and giving rigidity to the agitator structure. Although the agitator 5 is shown as formed or molded into an integral structure, it is of course to be understood that the parts may be made separate and connected together in any suitable manner.

30 In order to allow for ready adjustment of the agitator by the operator, a groove 21 is cut or formed in the hub 15 of the agitator. This groove denotes the water line, and it is a very easy matter to thus adjust the agitator to the point of maximum washing efficiency. In order to make this marking more pronounced, this groove may be painted or otherwise provided with suitable designating indicia or wording. It is of 35 course understood that the water line would necessarily vary as the depth of water in the tub is varied. A great deal of water would make it necessary to raise the agitator, while a small amount of water in the 40 tub would make it necessary to lower the agitator.

50 In order to enable an operator to make the adjustments accurately and with a minimum effort, it is necessary that the designated marking be made easily accessible. In the present construction where the agitating means or shaft passes through the bottom of the tub, there is no mechanism on the lid which would hinder or prevent the operator 55 from readily making the adjustment.

60 From the above disclosure, it will be clearly seen that I have provided a simple and efficient construction of agitator which may be readily and easily adjusted according to the depth of liquid in the washing machine tub. By this construction, it is always possible for the operator to secure a maximum 65 efficiency in the washing of clothes or other material.

Having thus disclosed my invention, I claim:

1. An agitator for washing machines and the like provided with a driving shaft, comprising a sleeve on said shaft and provided with a longitudinally extending groove, an impelling member slidable on said sleeve and provided with a rib adapted to seat in said groove, and means on said member for positioning said member at any desired height on 70 said sleeve.

2. An agitator for washing machines and the like provided with a driving shaft, comprising a sleeve on said shaft and provided with a longitudinally extending groove, an impelling member slidable on said sleeve and provided with a rib adapted to seat in said groove, and a thumb nut on said member for positioning said member at any desired 75 height on said sleeve.

3. An agitator for washing machines and the like provided with a driving shaft, comprising an impelling member slidable on the shaft and of greater specific gravity than the washing liquid, means for adjustably positioning the same on said shaft, and means for indicating the proper position to which 80 said agitator be adjusted to give the maximum washing efficiency.

4. An agitator for washing machines and the like provided with a driving shaft comprising an impelling member of greater specific gravity than the washing liquid, an upstanding hub on said member, means for adjustably positioning the same on said 85 shaft, and means on said hub and in full view of the operator for indicating the proper position to which said agitator be adjusted to give the maximum washing efficiency.

5. An agitator for washing machines and the like, provided with a driving shaft, comprising an impeller provided with a hub having a skirt portion, and spaced arms radiating from said skirt portion and merging into relatively narrow impelling elements.

6. An agitator for washing machines and the like provided with a driving shaft comprising an impelling member having a hub upstanding therefrom, means for adjustably positioning said member on said shaft, and means on said hub and in full view of the operator for indicating the proper position to which said agitator be adjusted to give the maximum washing efficiency.

7. An agitator for washing machines and the like provided with a driving shaft comprising an impelling member having a hub, means for adjustably positioning said hub along said shaft, and indicating means on said hub above said impelling member for designating the proper adjustment of said member relative to the level of washing fluid within the machine.

8. An agitator for washing machines and the like provided with a driving shaft com-

prising an impelling member having a hub thereon, and means for adjustably positioning said hub along said shaft, said hub having an annular groove therein located above said impelling member in full view of the operator and arranged to designate the proper operative position of the agitator mechanism when said groove is disposed substantially at the level of washing fluid in the machine.

10 In witness whereof, I herunto subscribe my name to this specification.

WALTER K. VOSS.
